(57) **CLAIM**

The ornamental design for a soap dispenser component, as shown and described.

DESCRIPTION

The patent or application file contains at least one drawing executed in color. Copies of this patent or patent application publication with color drawing(s) will be provided by the Office upon request and payment of the necessary fee.

1. Soap dispenser component

1.1 is a perspective view of a soap dispenser component showing my new design;

1.2 is a front side elevational view of the soap dispenser component of 1.1;

1.3 is a left end elevational view of the soap dispenser component of 1.1;

1.4 is a rear side elevational view of the soap dispenser component of 1.1;

1.5 is a right end elevational view of the soap dispenser component of 1.1;

1.6 is a top plan view of the soap dispenser component of 1.1;

1.7 is a bottom plan view of the soap dispenser component of 1.1.

The portions of the soap dispenser component shown in shaded blue coloring form no part of the claimed design.
